ATTORNEY

WITNESS:

R. A. Thomas

Patented July 7, 1925.

UNITED STATES PATENT OFFICE.

JAMES A. DOSSETT, OF PADUCAH, KENTUCKY.

SCREEN FRAME.

Application filed October 3, 1924. Serial No. 741,458.

To all whom it may concern:

Be it known that I, JAMES A. DOSSETT, a citizen of the United States, residing at Paducah, in the county of McCracken and State of Kentucky; have invented new and useful Improvements in Screen Frames, of which the following is a specification.

My present invention has reference to improvements in fly screens in which means is provided for permitting and for inducing the escape of flies from the rooms provided with the screens.

A further and important object of the invention is the construction of frames for either screen door or window frames in which the upper, and if desired, intermediate rails are formed with guideways and exit openings, the guideways being covered by the screening and serve to induce flies traveling upwardly on the screen to find an exit through the openings to the exterior of the room in which the screen is arranged, and thereby ridding the said room of the insects.

It is a still further and important object to produce rails for fly screen frames which are channeled longitudinally and bored at determined intervals by a gang of conical bits and thereafter cut centrally and longitudinally to provide two separate rails, each being thus provided with the guideways and exit openings for the flies or other insects.

To the attainment of the foregoing and other objects which will present themselves as the nature of the invention is better understood, reference is to be had to the drawings which accompany and which form part of this application.

In the drawings:

Figure 1 is a front elevation of the upper portion of a fly screen in accordance with this invention.

Figure 2 is a fragmentary perspective view to illustrate the manner in which the screening may be arranged upon the inner face of the frame.

Figure 3 is a perspective view of the rail that forms the essential feature of my invention.

Figure 4 is a sectional view approximately on the line 4-4 of Figure 1.

Figure 5 is a plan view of the strip which is channeled and bored, prior to the central cutting thereof to produce two of the rails illustrated in Figure 3.

Figure 6 is a sectional view on the line 6-6 of Figure 5.

It is, of course, to be understood that my improvement is equally adaptable to door or window screens. The stiles 1 of the frame are of the usual construction as may be the lower rail. The upper rail, and if desired, intermediate rails, however, are constructed in a novel manner which I will now describe.

As disclosed in Figures 5 and 6 of the drawings, the upper stiles are formed from a strip of wood of a desired length and thickness. The strip is preferably channeled longitudinally on one of its edges and is arranged beneath a gang of equi-distantly spaced cone-shaped bits for boring the said strip to a determined depth.

If desired, and as disclosed by the full lines in Figure 2 and by the dotted lines in Figures 5 and 6, the strip may be provided with transverse openings at the terminal of the conical openings made by the bits. The strip is then cut centrally and longitudinally whereby a single strip produces two rails 2. The channeling of the strip before the cutting thereof into rails, provides the lower edge of each rail with a longitudinally depressed portion 3 and a shoulder 4. The inwardly inclined cone-shaped openings provided by boring the strip provide the rails 2 with guide passages 5.

In the construction disclosed in Figure 1 of the drawings, a screen 6 is arranged over the frame and secured thereto by tacking and by beads 7. The beads that are arranged on the rails 2 are arranged a suitable distance below the terminal of the flared directing passages 5, so that these ends of the passages provide

exit openings 8 for the flies.

The screen is secured on the outer face of the frame and the natural tendency of flies or like insects is to travel upwardly. The walls 4 arranged below the flared passages 5 serve as directing means for the insects, and as stated, the insects will find an outlet through the openings 8, and in this manner the room in which the screen is arranged is soon rid of flies or like insects.

In Figure 2 the rail construction is as above described, except in this instance, the screen 6 is tacked on the wall 3' of the rail 2' and is likewise let in channels or grooves on the stiles. Also in this instance the flared passages 5' terminate in laterally extending openings 9. On the V-shaped lugs

- 10 of the rail provided between the flared passages 5' I tack a strip preferably of mesh, and indicated by the numeral 11. In this instance the flies crawling up the screen 6' ⁵ will be directed by the plate 11 into the flared passages 5' and from thence through the openings 9 to the atmosphere or, to the exterior of the room in which the screen is arranged.
- 10 From the foregoing description, when taken in connection with the drawings, it will be noted that I have produced a rail construction for fly screen frames that may be cheaply manufactured and which provides a simple but novel and thoroughly

efficient means for ridding rooms of flies without necessitating the obnoxious and cruel method of exterminating the insects.

Having described the invention, I claim:—

A method for producing upper or intermediate rails for fly screen frames comprising longitudinally channeling a wooden member boring it from the inner wall of the channel to provide spaced cone-shaped depressions, and dividing said strip centrally ²⁰ and longitudinally to provide two rails.

In testimony whereof I affix my signature.

JAMES A. DOSSETT.
